JAMES McKECHNIE AND HARTLEY BLYTH PRATT, OF BARROW-IN-FURNESS,
ENGLAND, ASSIGNEES TO VICKERS LIMITED, OF WESTMINSTER, LONDON,
ENGLAND.

AEROSTAT STRUCTURE OF RIGID AIRSHIPS.

1,308,291

Specification of Letters Patent.

Patented July 1, 1919.

Application filed March 25, 1919. Serial No. 285,109

To all whom it may concern:

Be it known that we, Sir JAMES McKECHNIE, K. B. E., and HARTLEY BLYTH PRATT, both subjects of the King of Great Britain, residing at Naval Construction Works, Barrow-in-Furness, in the county of Lancaster, England, have invented certain new and useful Improvements in or Relating to the Aerostat Structure of Rigid Airships, of which the following is a specification.

This invention relates to the aerostat structure of rigid airships of the kind in which tubular flexible members are employed, inflated under pressure to give the desired rigidity, and has for its chief object to provide the necessary strength and rigidity with a minimum weight of material.

According to this invention, the aerostat structure comprises a girder structure formed of a series of inflatable flexible tubes jointed together at their ends.

A long tube, whether of rigid or flexible material, inflated with gas under pressure, resists compression or bending loads as long as the longitudinal tension stress in the material due to the internal pressure is sufficient to maintain the whole of the tube material in tension when subjected to the said loads. The tubular girders of the framework are of fabric or other flexible material having the necessary tensile strength and the tubes are inflated with air or other gas compressed sufficiently to insure resistance to the compression, bending or other loads to which they may be subjected as part of an aerostat structure.

The framework may be substantially similar in general arrangement to the framework of the present type of rigid airship, that is, it may comprise longitudinal girders, transverse frames of polygonal shape built of a series of shorter similar girders, external diagonal wires between the joints of the longitudinal and transverse girders, transverse wiring to fix the shape of the transverse frames and suspension wiring to suspend the weights from the transverse frames.

In order that the said invention may be clearly understood and readily carried into

effect we will describe the same more fully with reference to the accompanying drawings, in which:

55

Figures 1 and 2 are views at right angles to each other showing the general arrangement of part of an aerostat structure embodying this invention, and

60

Figs. 3 and 4 are detail views, at right angles to each other, of the connections between the hollow girder ends.

65

A is the girder tube provided at the ends with the conical metal caps a on which they are wired at a'. B, B are the external diagonal wires, B', B' the transverse wiring and B², B² the suspension wiring. C, C are the joint members to which the girder ends are secured.

70

The tubes A are preferably woven seamless and the fabric proofed with rubber or other air proof composition. It may be of single or multiple ply linen or cotton or may be woven of metallic wire. As shown especially at the right hand side of Fig. 4 75 the tubes terminate in the truncated conical end pieces a preferably pressed from sheet metal and provided with the cylindrical part a² strengthened at the edge by the lip a³, the end of the tube fabric extending over 80 the part a² and being wired firmly on so as to provide a gas tight joint. Inflation of the tube to the desired pressure is provided for by a non-return valve of any suitable type fitted to the cap or end piece a.

85

To connect up the ends of the inflatable girders to form the aerostat structure the joint member C is provided with connecting lugs e at each side, four pairs of lugs being shown in Fig. 4 to connect up four girder ends. The conical tube ends a are provided with corresponding lugs a⁴ and bolts c', c² connect the parts together and form at one end a hinge which allows of angular adjustment of the girders around the connecting member. Diagonal wires B, as shown especially in Fig. 1, are carried between the connecting members C of adjacent transverse frames each formed by a set of short tubular girders A arranged to form a polygon by the aid of the radial transverse wires B' which connect up the members C of each frame to a central point. The diagonal wires B cross each other as shown in Fig. 1 between the 100

95

100

longitudinal tubular girders A, which are of greater length than the girders forming the transverse frames, the wires B being conveniently connected to lugs c³ on the outer ends of the bolts c'. The radial wires B' and the suspension wires B² by which the weights are supported on the transverse frames may both be connected to lugs c⁴ on the connecting members C. Circumferential cords or wires, not shown, run freely through connections on the inflated tubes to transmit the pressure of the gas bags to the tubular girders. The general construction is analogous to that commonly employed, with such modifications as are necessary to adapt the construction to the inflated girder structure.

The internal pressure required to give the necessary rigidity can readily be calculated for an airship of given dimensions; 20 lbs. per square inch may be taken as an approximate figure for an airship of moderate size. The tubes may be provided with pressure gages to show the pressure to which they are inflated.

What we claim and desire to secure by Letters Patent of the United States is:—

1. An aerostat structure for rigid airships, comprising a girder construction formed of inflatable flexible tubes attached at their ends to adjoining members to form transverse frames connected together by longitudi-

dinal tubular girders, for the purpose specified.

2. An aerostat structure for airships comprising a girder construction formed of inflated tubes attached at their ends to adjoining members, to form transverse frames connected by longitudinal inflated tubes.

3. An aerostat structure for rigid airships comprising a girder construction formed of inflated flexible tubes attached at their ends to adjoining members, by means of metal end pieces or caps, to form transverse frames connected by longitudinal inflated tubular girders.

4. An aerostat structure for rigid airships comprising a girder construction formed of inflated flexible tubes attached at their ends to adjoining inflated flexible tubes by means of metal end pieces or caps, to form transverse frames connected by longitudinal inflated tubular girders, said frames provided with radial and diagonal wire stays.

5. An aerostat structure for rigid airships comprising a girder construction formed of a number of inflatable flexible tubes hinged at their ends through connecting members, to form a series of transverse frames interconnected by girders and provided with radial diagonal wire stays.

JAMES McKECHNIE.
HARTLEY BLYTH PRATT.
